UNITED STATES PATENT OFFICE.

CHARLES K. PICKLES, OF PHILADELPHIA, PENNSYLVANIA, ASSIGNOR
TO JOHN A. BRILL, OF PHILADELPHIA, PENNSYLVANIA.

WALK-OVER CAR-SEAT.

SPECIFICATION forming part of Letters Patent No. 784,426, dated March 7, 1905.

Application filed September 9, 1903. Serial No. 172,432.

To all whom it may concern:

Be it known that I, CHARLES K. PICKLES, a citizen of the United States, and a resident of the city and county of Philadelphia, State of Pennsylvania, have invented a new and useful Improvement in Walk-Over Car-Seats, of which the following is a specification.

Heretofore seats of this type have been made with a plurality of links at each end of the seat by means of which the back has been brought over the seat-cushion to reverse the seat.

The object of my invention is to simplify this construction by utilizing only one link at each end of the seat and also to provide mechanism which coöperates with said links to shift the seat-cushion in unison with the back. My invention accomplishes this and other objects.

For a more particular description of certain embodiments of my invention reference is to be had to the accompanying drawings, forming a part hereof, in which—

Figure 1 is an end elevation of a seat provided with my improvement, the end plate being removed to show the mechanism. Fig. 2 is a front elevation of the same, a part being shown in sections. Fig. 3 is a plan view of the end of the seat next the stanchion. Fig. 4 shows a part of the mechanism in perspective. Figs. 5 and 6 show in perspective a slightly-modified structure. Fig. 7 shows one form of seat-support. Fig. 8 discloses one face of an end plate used in the structure illustrated in Fig. 4. Figs. 9 and 10 show a further modification, and Figs. 11, 12, 13, and 14 show certain details connected with the same. Figs. 15 and 16 show another modification. Fig. 17 shows a shaft-connecting mechanism.

Throughout the various views similar reference characters designate similar parts.

While my improvement may be utilized in many forms of car-seats, I will show and describe a form which is particularly adapted to convertible cars with a central aisle and transverse seats. In this structure one end of the seat is supported by a panel 1 and the other end by any suitable legs 2, and the panel and legs are united by foot-rests 3 and tubular

cross-bars 4, which extend from sockets 5 in the panel 1 through adjustable sockets 6 at the upper extremity of the legs 2, and these cross-bars 4 may be clamped in place by these sockets by cap-screws 7. The said cross-bars 4 do not terminate at the sockets 6, but extend beyond them to the inner end of the seat, where their ends rest in sockets 8 on the end plate 9, and to this plate they are fixed. The plate 9 may be given any suitable shape, although it is preferably made, as shown, with seats 10 on its upper edge and sockets 11 and 12, which are centrally located between the sockets 8 and on the same side of the plate. The other side of this plate 9 is provided with a strengthening-flange 13 and may be given any suitable ornamentation. Instead of the seats 10 (shown in Figs. 5 and 6) stops 14 and 15 may be employed, as shown in Fig. 4, as either obtains substantially the same results.

Parallel shafts 16 and 17 are journaled in the sockets 11 and 12 and also in similarly-disposed sockets 18 and 19 in the panel 1, so that said shafts may revolve freely. These sockets 18 and 19 are preferably formed in a flanged angle-plate which has a lower vertical web 20, in which the cross-bars 4 are fixed in sockets 5, and an upper horizontal web 22, which is provided with a recess 23, through which stanchion 24 passes. A lug 25 on the outer part 26 of the panel 1 supports a part of the web 22. The web 20 is fixed to the part 26 by cap-screws 27 or other suitable means.

The rotary shafts 16 and 17 are each provided with cranks 28 with crank-pins 29, which engage a connecting-link 30^a, so that the shafts 16 and 17 will always turn together and in unison. These shafts are also provided with eccentrics 30 and 31 adjacent to each end of each shaft, these eccentrics being oppositely disposed—that is, so that the eccentric 30 will have its most eccentric portion elevated to the top of its throw, while the other eccentric, 31, will be correspondingly depressed, and vice versa, so that the seat-brackets 32, which rest on said eccentrics, will be tilted or inclined in unison therewith. The brackets 32 are each provided with two openings 33 and 34, the former being on the eccentric 30

and closely fitting the same, while the latter is elongated enough to permit the eccentric 31 to turn freely therein. The upper surfaces of the brackets 32 are adapted to receive and support a cushion 35, so that this cushion will always be properly inclined with regard to the back 36.

At each end of the back 36 are plates 37 and 38, with oppositely-disposed projections 39 and 40, which are provided with pins 41, which are engaged by links 42, which are fixed to the shafts 16 and 17, respectively, adjacent to the plate 9 and vertical web 20. The links 42 are vertically disposed—that is, they swing in a vertical plane, a structure which is altogether different from one in which they swing in a horizontal plane, as is apparent. In the modification shown in Figs. 5 and 6 the plates 37 and 38 are provided with additional projections 43, which are adapted to rest in the seats 10 to limit the movement or swing of the back 36. The same result is accomplished by the stops 14 and 15, which the links 42 rest against at the limits of their movement. These links 25 are preferably flanged and provided with recesses 44 to enable them to clear the shafts 16 and 17. The back 36 is also provided with a hand-strap 45, which is secured to a staple 46, secured at its upper and inner edge, as is apparent from Fig. 2.

As the walk-over back is some distance from the stanchion 24, a guard is advisable, so I provide two links 47 and 48, the latter of which is smaller and is pivoted to the stanchion 24 at 49 and at its other end is pivoted to the link 47 at 50. This link 47 may be given any suitable form and is pivoted to the back 36 at 51. Another form of guard is shown in Fig. 15, in which the link 48 is dispensed with. The link 47^a is made longer than the link 47 and provided with an elongated slot 47^b, through which a pin 52 protrudes to secure the link 47^a to the stanchion 24 with a sliding and pivotal connection. The other end of the link 47^a is secured to the back 36 by a pivotal connection. The seat may be provided with either of these guards, or they may be omitted entirely, as desired.

From the foregoing the operation of this embodiment of my invention will be readily understood. Assuming the parts to be in the position indicated in Fig. 1, the seat is reversed by swinging the back 36 on the links 42, which will be caused to move in unison and rock the shafts 16 and 17, with their eccentrics 30 and 31, and shift the brackets 32 and seat 35, as described above, until the movement of the links is terminated by the stops 14 and 15 or by the contact of the projections 43 with the seats 10. The guard swings on its pivots or its pivot and slide, as is apparent.

It is not necessary that the cushion 35 be supported on the brackets 32, as these may be replaced by rockers 53, which rest on the cross-bars 4. These rockers 53 each comprise two

vertical webs 54, united by curved and horizontally-disposed webs 55 and 56, and the web 55 is extended to form rests 57 with lugs 58 for the cushion, and these rests 57 are united with the web 56 by cams 59. The web 56 is also provided with depending lugs or guides 60. The opening between the webs 54, 55, and 56 is sufficiently large to allow the shafts 16 and 17 to pass freely therethrough and not interfere with the movement of the rockers 53, and the cranks 28^a, which are fixed to said shafts, are so disposed that their connecting-links 30^a will each have a lug 30^b engaging the guides 60 and cause the said rockers to slide on their cams 59 on the bars 4 and tilt 80 and shift the cushion 35 in unison with the back 36 when the seat is reversed.

A simpler construction with a fixed seat-cushion is shown in Figs. 15 and 16, in which the cushion 35 is fixed to the seat-panel and legs 2^a, and the rotary shafts 16 and 17 are mounted in hangers 61, which are fixed to the under surface of the cushion 35, and stops 62 for the links 42 are also secured to the cushion, as the plates 9 and rails 4 are not used in this structure.

It is obvious that my improved mechanism for shifting the back may be used either with or without the seat-shifting mechanism or the guard, as described above, and on seats extending either entirely or partially across the car. It may also be used when the outer ends of the seats are between the stanchions or on any other structure when walk-over seats are applicable. For these reasons I do not regard my invention as restricted to the embodiments herein described, but regard it as applicable to all structures which come within the terms of the annexed claims.

What I claim is—

1. In a reversible car-seat or similar device, a single link pivoted to each end of said back and to said support, said pivots being out of axial alignment, and means for supporting said links at the limits of their movements.
2. In a reversible car-seat or similar device, a support, a back, single links pivoted to said back and fixed to shafts journaled in said support, and means for causing said shafts to rotate in unison when the seat is reversed.
3. In a reversible car-seat or similar device, a support, a back, single links pivoted to said back and fixed to parallel shafts journaled in said support and means secured to said shafts for causing them to move in unison when the seat is reversed.
4. In a reversible car-seat or similar device, a support, a back, single and vertically-disposed links pivoted to said back and pivotally connected to said support, one of said links being fixed to a shaft and means connected with said shaft for causing said links to move in unison.
5. In a reversible car-seat or similar device, a support, a back, single links at each end

- of said back, horizontally-disposed parallel shafts journaled in said support and to which said links are fixed, cranks fixed to said shafts, and a link connecting said cranks.
- 5 6. In a reversible car-seat or similar device, a support, a back with projections extending out of the plane of said back in one direction only from each lower edge of each end, two pivots on said support, said pivots being out 10 of axial alinement, and means connecting said projections and pivots.
7. In a reversible car-seat or similar device, a support with horizontally-disposed shafts journaled therein, a back with oppositely-disposed 15 projections extending from its plane adjacent to its lower edge, and links connecting each projection with a shaft so that each shaft is connected with said back by one link only.
- 20 8. In a reversible car-seat or similar device, a support comprising cross-bars adjustably mounted in legs, plates uniting the ends of said bars, shafts journaled in said plates, a back, oppositely-disposed projections, each 25 extending in one direction from the plane of said back, and means for pivotally connecting each projection with one shaft.
9. In a reversible car-seat or similar device, a support comprising cross-bars adjustably 30 mounted in legs, plates uniting the ends of said bars, shafts journaled in said plates, a back with oppositely-disposed projections each extending in one direction out of the plane of said back, and identical means for connecting 35 each projection with one shaft.
10. In a reversible car-seat or similar device, a support, comprising in its construction cross-bars united at their ends by plates, shafts journaled in said plates, a back with oppositely- 40 disposed projections extending from the plane of its surface, links connecting each projection with one shaft, and means for causing said shafts to move in unison when the seat is reversed.
- 45 11. In a reversible car-seat or similar device, a support provided with cross-bars united at their ends by plates, a shaft journaled in said plates a back; two oppositely-disposed 50 projections protruding from the plane of said back, a link connecting one of said projec-
- tions with said shaft, and means for pivotally connecting the other projection with said support.
12. In a reversible car-seat or similar device, a support provided with cross-arms 55 united at their ends by plates, a shaft journaled in said plates, a back, two oppositely-disposed projections protruding from the plane of said back, a link connecting one of said projections with said shaft, means for connecting 60 the other projection, with said support, and means for connecting said first-mentioned means and said link so that they will act in unison when the seat is reversed.
13. In a walk-over car-seat or similar device, a seat-support, a back, shafts journaled in said support, a seat-cushion, links connecting said shafts and back, eccentrics on said shafts, and means connecting said eccentrics and seat-cushion so that the seat and back are 65 moved in unison when the seat is reversed.
14. In a reversible car-seat or similar device, a seat-support with shafts journaled therein, a back, links connecting said back and shafts, eccentrics on said shafts, brackets en- 70 gaging said eccentrics a seat-cushion resting on said brackets so that when the seat is reversed, the back and seat-cushion will be moved in unison.
15. In a reversible car-seat or similar device, a seat-support with shafts journaled therein, eccentrics mounted on said shafts, brackets engaging said eccentrics and a seat 75 secured to said brackets.
16. In a reversible car-seat or similar device, a seat-support with shafts, journaled therein, means for causing said shafts to move in unison, oppositely-disposed eccentrics se- 80 cured to said shafts so that when the most eccentric part of one eccentric is elevated, the corresponding part of the other is depressed, a seat-cushion, and means connecting said cushion and eccentrics.
- Signed at the city of Philadelphia, county of Philadelphia, and State of Pennsylvania, 95 this 28th day of August, 1903.
- CHARLES K. PICKLES.
